US00D719862S

(12) **United States Design Patent**
Fiedler et al.

(10) **Patent No.:** **US D719,862 S**
(45) **Date of Patent:** **** Dec. 23, 2014**

(54) **HOME CENTER MANAGER**

(71) Applicant: **Fibar Group sp. z o.o.**, Poznań (PL)

(72) Inventors: **Maciej Fiedler**, Poznań (PL); **Lukasz Gdyk**, Dabrowka (PL); **Jakub Hermanski**, Wagrowiec (PL)

(73) Assignee: **Fibar Group sp. z o.o.** (PL)

(**) Term: **14 Years**

(21) Appl. No.: **29/494,203**

(22) Filed: **Jun. 18, 2014**

(30) **Foreign Application Priority Data**

Jan. 7, 2014 (EP) 002381137-0001

(51) **LOC (10) Cl.** **10-05**

(52) **U.S. Cl.**

USPC **D10/106.95**

(58) **Field of Classification Search**

USPC D10/104.1, 106.1, 106.95; D14/137, D14/240; D19/2

(57) **CLAIM**

The ornamental design for a home center manager, as shown and described.

DESCRIPTION

FIG. 1 is a top front right-side perspective view of an embodiment of a home center manager showing our new design;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a top front right-side perspective view of another embodiment of a home center manager showing our new design;

FIG. 9 is a front elevation view thereof;

FIG. 10 is a back elevation view thereof;

FIG. 11 is a right-side elevation view thereof;

FIG. 12 is a left-side elevation view thereof;

FIG. 13 is a top plan view thereof; and,

FIG. 14 is a bottom plan view thereof.

The broken line showing is included for the purpose of illustrating portions of the "article" and forms no part of the claimed design.

1 Claim, 8 Drawing Sheets
